ELECTRIC FIRE

Norman Mindham Bell, Northampton, England

Application November 8, 1930, Serial No. 494,273,
and in Great Britain November 12, 1929

1 Claim. (Cl. 219—34)

This invention relates to the incorporating of electric fire elements into a faience and/or the surround and/or mantel slabbed in cement or other material; the arrangement would be commonly known as a "built-in" fire.

The objects of the invention are to provide an electric fire such that a tile or faience mantel or surround can be sent out or supplied with the fire in one unit, ready for fixing, and to so construct or arrange the parts that a tile or faience mantel with return ends fitted with the fire can be fixed to a flat wall without any recess in the brickwork being necessary. In my invention, also, the factor of danger will to a very great extent be eliminated, since all bolts and other metal used in the construction will be embedded in the cement or other material used for slabbing.

According to the invention I prepare a fire opening in the tile mantel or surround of a suitable size to receive one or more element bars of any suitable or standard width or pattern. The necessary number of bolts or the like are let into the cement or other backing of the tile or faience work, for the purpose of fixing the elements in position. These elements may either be secured directly to the backing or carried by a form of sub-frame or the like; they may be wired in the usual manner, and are preferably connected through a porcelain terminal block, which may also be fixed in a position somewhere below the element bars and approximately in line with the switches, which, in the case of a tile or faience mantel with return ends, are preferably fitted on the return end on either side, as may be found most convenient.

A space may be left below the elements, this space being filled with a faience or other fret or trivet, which may be loose and removable for the purpose of inspecting the wiring or replacing any part of the fire at any time.

The cement backing of the fireplace may be boxed out around the fire parts to a sufficient depth from back to front to give them protection and to give sufficient hand room for removing and replacing any part. This boxed backing is preferably closed at the back by means of a sheet of asbestos-cement, or other material.

The fireplace preferably stands on a raised hearth, but an ordinary low hearth may be used if desired. If a raised hearth is used, however, the flexible insulated or other wire from the main may be unobtrusively introduced through and under the raised hearth to the terminal block.

In further describing this invention reference

will be had to the accompanying sheet of drawing which illustrates a suitable method of carrying my said invention into effect. Figure 1 is a vertical sectional elevation through an electric fireplace on line $x-x$ of Figure 2.

Figure 2 is a front elevation of such a fireplace.

Figure 3 is an elevation showing this application of the invention from the back of the fireplace.

Referring to the drawing I provide a tile or other surround r the opening in which may be returned on the inside and/or may have secured thereto a suitable cement or other boxing or the like p as previously described; I may mount element bars e on a sub-frame or the like which may consist of two vertical metal strips d to which the element bars e may be bolted or otherwise secured. The upper ends of the metal strips may be arranged to pass in front of a horizontal cross bar c which is preferably carried at either end by being let into the cement boxing p on the surround. The lower extremities of the vertical strips may be arranged to engage bolts or the like which are projecting from and secured to the cement boxing p , said strips being held in position by wing or other nuts w . A porcelain terminal block j may be carried by a further horizontal bar o which is preferably carried by the lower portions of the aforesaid vertical strips, from whence the current is conducted through terminals h and connecting wires g to terminals t on the element bars e suitable switches s being disposed in the circuit, the switch-box k for which, in the case of a tile surround having a return end may as illustrated, be placed on the inside of said return. The feed wires m from the main may be passed through recesses or cut away portions in the hearth v or a wall plug may be provided at the back of the fireplace.

I may if necessary provide a ventilator a above the element bars e in order to convey convected heat rising from the said element bars e , a space f being provided above the said element bars e for the purpose of creating an air current. A preferably detachable faience or other fret or trivet l may be incorporated which may if necessary be perforated for the purpose of forming an air current in lieu of the space f aforementioned. The whole of the back of the fireplace surrounded by the cement boxing may be covered or encased by a sheet b of asbestos, metal or other material, secured in position by screws or bolts n .

When it is desired to withdraw the element bars and sub-frame for examination or replacement, the trivet l is removed, and the wing nuts w

removed; the whole of the sub-frame and its fittings can then be drawn downwards and forwards through the fire opening in the front of the tile or other surround; the various connecting wires may be suitably coiled to enable this operation to be carried out without disconnecting them from their terminals.

It will be understood that I do not wish to limit the use of my invention to a flat surround having returned ends, as it is capable of being applied to flat recessed and splayed surrounds fitting into mantels or any convenient fireplace openings. The invention can also be employed in connection with inset fires.

15 I claim:

A built-in-electric hearth, comprising a fireplace surround, a boxed backing disposed rearwardly of said surround, a horizontal bar having

its ends secured in the opposite side walls of said backing, a vertical frame disposed within the backing and resting at its upper end against said horizontal bar, means for releasably securing the lower end of said frame to said backing, electric heating elements and their associated terminals, a terminal block and lead wires mounted on said frame, said fireplace surround having an aperture smaller than the front area of the backing and in which aperture the heating elements are exposed to view, said surround having a ventilating aperture above said first aperture and a removable member below said aperture, the removal of said member affording access to said releasable securing means whereby the frame and all the members carried thereby may be removed and replaced as a unit.

NORMAN MINDHAM BELL.
